[57] **CLAIM**

The ornamental design for a modular conduit support, as shown and described.

DESCRIPTION

FIG. 1 is a left side perspective view of a modular conduit support showing our new design;

FIG. 2 is a right side perspective view thereof;

FIG. 3 is a right side elevational view thereof;

FIG. 4 is a front elevational view thereof;

FIG. 5 is a rear elevational view thereof;

FIG. 6 is a left side elevational view thereof;

FIG. 7 is a top plan view thereof; and,

FIG. 8 is a bottom plan view thereof.

FIG. 1.

FIG. 2.

FIG. 4.

FIG. 3.

*FIG. 5.**FIG. 6.**FIG. 7.**FIG. 8.*
